UNITED STATES PATENT OFFICE.

GILBERT CONGDON, OF CATONSVILLE, MARYLAND.

DESIGN FOR A TOY BANK AND CLOCK-CASE.

45,372.

Specification for Design.

Patented Mar. 10, 1914.

Application filed December 18, 1913. Serial No. 807,562. Term of patent 7 years.

To all whom it may concern:

Be it known that I, GILBERT CONGDON, a citizen of the United States, residing at Catonsville, in the county of Baltimore and State of Maryland, have invented a new, original, and ornamental Design for a Toy Bank and Clock-Case, of which the following is a specification, reference being had to the accompanying drawing, forming part thereof.

The figure is a perspective view for a toy bank and clock case, showing my new design.

I claim:

The ornamental design for a toy bank and clock case, as shown.

GILBERT CONGDON.

Witnesses:

JULIA B. ROBINSON,
SARAH SCHOTTA.
